SLIPPER SOCK

Robert S. Servin, Jenkintown, Pa., assignor to Robert Hosiery Mills, Inc., Trappe, Pa., a corporation of Pennsylvania

Filed May 29, 1962, Ser. No. 70,346

Term of patent 14 years

(Cl. D7—7)

FIGURE 1 is a perspective view of a slipper sock showing my new design as it appears in wearing position; FIGURE 2 is a top plan view thereof; and FIGURE 3 is a bottom plan view thereof.
I claim:

The ornamental design for a slipper sock, as shown.
